ELECTRIC SWITCH

Arnold A. Bluemle, Anderson, Ind., assignor to
 General Motors Corporation, Detroit, Mich., a
 corporation of Delaware

Application September 7, 1942, Serial No. 457,552

7 Claims. (Cl. 200—77)

This invention relates to manually closed, spring opened electric switches and it aims to provide a switch having means for maintaining adequate pressure between the contacts of the switch although the force applied to the operating handle of the switch may vary within certain limits, and having means for obtaining a quick break of an electrical circuit regardless of the rate of return of the handle to the open position of the switch.

Further objects and advantages of the present invention will be apparent from the following description, reference being had to the accompanying drawing wherein a preferred embodiment of the invention is clearly shown.

In the drawing:

Figs. 1, 2 and 3 are longitudinal sectional views of the switch showing its movable contact in different positions.

The switch comprises a housing 10 enclosing 20 fixed contacts 11 and a movable contact 12. Housing 10 is closed by a terminal plate 13 supporting terminal screws 14 carrying the contacts 11 and attached to the housing 10 by screws 15. Contact 12 is attached to a metal tubular rivet 16 and is insulated therefrom by washer 17, bushing 18 and plate 19 all of insulating material. Rivet 16 is mounted on a sleeve 20 slidably supported by a bearing 21 provided by housing 10 and having a stop flange 22 engageable with the left end of said bearing. A spring 23, interposed between flange 22 and plate 19, urges the rivet 16 against a washer 24 retained by a flange 25 on the left end of sleeve 20.

A rod 26 is slidable through the sleeve 20 and has a flange 27 engaging the flange 25. The right end of rod 26 carries a flange 28 located in a recess in a sleeve 29 and confined therein by a handle 30 attached to the sleeve 29 by a screw 31 engaging a groove 32 in the sleeve 29. Handle 30 has a tubular part 33 telescoping with a tubular part 34 provided by housing 10. Part 34 is threaded to receive nuts 35 and 37 with a washer interposed. Space 38 receives an instrumental panel (not shown) having a hole through which the part 34 extends. Nuts 35 and 37 are tightened against the panel to secure the switch thereto. A spring 40, located between the sleeve 29 and a washer 41 engaging a shoulder 42 provided by the housing 10, urges the handle 30 and rod 26 toward the right and holds the movable contact 12 away from the fixed contacts 11 and the stop flange 22 against the bearing 21.

The sleeve 20 is provided with grooves 43 and 55

44 separated by a ridge 45. Groove 43 normally receives balls 46 located in pockets 47 closed by plugs 48 and urged into said groove by springs 49 maintained by the plugs 48 in an initial state of compression.

Fig. 1 shows the switch in the OFF position. When moving the handle 30 to the left to close the switch as shown in Fig. 2, the sleeve 29 engages the sleeve 20 which transmits motion to the contact 12 through the spring 23 to cause said contact to engage contacts 11 with yielding pressure. Rivet 16 should loosely fit the sleeve 20 so that the pressure between the fixed and movable contacts will be substantially equal. Fig. 2 shows that the spring 23 has been compressed further than in Fig. 1 thereby increasing the contact pressure. Maintenance of the engagement of the contacts is effected by the spring 49 which act through the balls 46, then received by groove 44, in such manner as to apply force against the right inclined side of ridge 45 thus to urge the sleeve 20 toward the left. When the contact 12 is at 12a in Fig. 1, the ridge is at 45a and the balls are at 46a. As the sleeve 20 continues its movement toward the left, the peak of the ridge 45 passes between the balls 46, thereby causing the springs 49 to become effective to maintain the sleeve 20 in position for causing the spring 23 to maintain the contact 12 in engagement with contacts 11. Handle 30 may move right a substantial amount from the position shown in Fig. 2 before the sleeve 20 is caused to move right. Therefore easing of pressure on the handle 30 will not effectively change the pressure between switch contacts. In fact handle 30 might be moved to the right by spring 40 sufficiently to take up the clearance between flange 27 and rod 26 and flange 25 of sleeve 20 and to cause thereafter some movement of the sleeve 20 toward the right, but the movable contact 12 will remain in engagement with fixed contacts 11 as long as balls 46 engage the right side of ridge 45. This feature is advantageous for example when the switch is used to control the circuit of an electric starting motor. When the switch has been closed, it is not necessary to exert upon the handle 30 that force required to close the switch. Engine starting may require several seconds and the car driver is apt to ease up the pressure upon the switch handle unconsciously; but this will not cause the switch to open.

To open the switch, the handle 30 is released to permit spring 40 to expand and to move rod 26 right to separate sleeve 29 from sleeve 20 and to cause flange 27 to engage flange 25. Then

the sleeve, 20 will start to move right, but the contact 12 will still remain in engagement with contact 11. This engagement will be maintained until ridge 45 arrives substantially at 45b in Fig. 3, whereupon spring 49 will cause the balls 46 to urge the sleeve 20 right ahead of movement of rod 26 thereby causing the sleeve 20 to move toward the sleeve 29 and the washer 24 to engage the rivet 16 and thus cause the sleeve 20 to separate the contact 12 from the contacts 11 although the sleeve 29 has moved no further to the right than the position shown in Fig. 3. In this way, the breaking of the circuit by the switch is caused to take place rapidly independently of the rate of movement of handle 30 to the right. Therefore it is impossible to cause undue arcing at the switch contacts by causing the handle 30 to move to the right relatively slowly.

I claim:

1. In an electric switch the combination comprising stationary contacts; a movable contact; a sleeve having cam means and supporting the movable contact; a shaft slidably supported by the sleeve; releasable holding means cooperating with the cam means; a plunger; spring means resisting movement of the plunger in one direction; a second spring biasing the movable contact toward the stationary contacts; means to actuate the plunger in one direction, said plunger when actuated in said one direction is capable of moving a certain distance relative to the sleeve before engaging the sleeve to move same and the movable contact into engagement with the stationary contacts, said sleeve gradually compressing the second spring after the movable contact engages the stationary contacts to increase the contact pressure between the contacts, and said releasable holding means cooperating with the cam means to hold the sleeve against retrograde movement on slight retrograde movement of the plunger so as to maintain the full pressure between the contacts up to the time the plunger moves the sleeve a certain distance in the reverse direction when the holding means moves the sleeve relative to the movement of the plunger in its reverse direction to separate the movable contact from the stationary contacts with a snap action.

2. A switch comprising in combination; a housing; a closure for the housing and carrying stationary contacts; an inner sleeve slidably supported within the housing; an outer sleeve slidably supported by the housing and manually operated for moving the inner sleeve in one direction; a rod fixed to the outer sleeve and extending through the inner sleeve; lateral means carried by the rod for holding the inner sleeve in assembled relation with the rod and also for moving the sleeve in the opposite direction; a movable contact slidably and yeldingly supported on the inner sleeve; resilient means acting on the outer sleeve and causing the lateral means of the rod to engage and shift the inner sleeve to a certain position to hold normally the movable contact separated from the stationary contacts; and co-acting means carried by the housing and the inner sleeve operating to increase the contact pressure between the contacts after engagement thereof, and said coacting means also operating to move the inner sleeve relative to the rod to snap the movable contact out of engagement from the stationary contacts after predetermined movement of the outer sleeve toward its normal position.

3. A switch comprising in combination; a hous-

ing; a closure carrying terminals for the housing; a pair of spaced sleeves slidably and separately supported by the housing; a rod fixed at one end to the first sleeve and slidably supported by the second sleeve, said rod having provisions at the other end for maintaining the second sleeve on the rod so that said sleeves move together after predetermined movement of the first sleeve; a contact slidably supported on the second sleeve for bridging the terminals; a light spring for urging the contact in one direction; a heavy spring acting on the first sleeve to move the sleeves so that the contact is in a non-bridging position; cam means provided by the second sleeve; spring urged balls carried by the housing and engageable with the cam means; means for actuating the first sleeve and the rod in one direction against the action of the heavy spring; means carried by the rod for moving the second sleeve after predetermined movement of the rod for moving the second sleeve and the contact in the same direction to bridge the terminals and also to compress the light spring whereby full pressure contact is obtained, said ball means cooperating with the cam means to prevent retrograde movement of the sleeve upon slight return movement of the rod and also to move the sleeve with a snap action relative to the rod to separate the contact before the rod reaches its normal home position.

4. A switch comprising in combination; a housing; stationary contacts carried by the housing; a reciprocable sleeve supported by the housing; a reciprocable contact means mounted on the sleeve; spring means for urging the contact means against a stop provided by the sleeve; a reciprocable actuator slidably supported by the sleeve and having shoulders on opposite ends of sleeve to hold the sleeve in assembled relation with the actuator, said shoulders being spaced so that the distance therebetween is greater than the longitudinal length of the sleeve to provide for a lost motion between the sleeve and shoulders; spring means for urging the actuator in one direction, one of said shoulders engaging one end of the sleeve to separate the contacts; coacting means carried by the housing and the sleeve, said coacting means operating upon movement of the actuator causing one of the shoulders to move the sleeve and the reciprocable means to engage the stationary contacts with yielding pressure; coacting means carried by the housing and the sleeve to hold the reciprocable contact means under full pressure upon any slight retrograde movement of the actuator and also maintain full pressure contact between the contacts up to the time of separation when the coacting means functions to move the sleeve relative to the actuator to separate the contacts quickly; and means for limiting the movement of the sleeve toward the switch opening position.

5. In an electric switch the combination of a reciprocable sleeve; a cam secured to the sleeve and movable therewith, said cams having oppositely disposed sloping sides; a yeldable contact reciprocably mounted on the sleeve and actuated by the sleeve to open and closed positions; a shaft reciprocably mounted in the sleeve; a spring urging the shaft in one direction; means carried by the shaft at each end of the sleeve for actuating the sleeve in one or the other direction, said means being disposed so that when one engages the sleeve the other will be spaced from the sleeve; and yeldable holding and actuating means operating with the cam so that when the shaft

is actuated to move the sleeve in one direction to move the contact in the closed position, the yieldable means will pass from one sloping side to the other to operate as the holding means to hold the sleeve against retrograde movement on slight retrograde movement of the shaft so as to prevent arcing between the contacts and said means operating as the actuating means when the shaft and sleeve are moved a certain distance in the reverse direction to move the sleeve relative to the shaft thereby separating the contacts quickly.

6. In an electric switch, the combination of a housing; a reciprocable sleeve mounted in the housing; a shaft reciprocably mounted in the sleeve; abutments carried by the shaft for moving the sleeve with the shaft in either direction; a contact reciprocably mounted on the sleeve and moved into a closed position when the sleeve is actuated by one of the abutments of the shaft; a cam secured to the sleeve and movable therewith, said cam having oppositely disposed inclined surfaces to provide a ridge; a spring urged member supported relative to the sleeve, said member being urged against one of the surfaces when the contact member is in an open position and adapted to pass over the ridge and engage the other surface when the contact member is in the closed position, said means when engaging the last mentioned surface holding the sleeve against retrograde movement on slight retrograde movement of the shaft and maintain the contact in the closed position up to the time the other abutment on the shaft engages the sleeve to move same a certain distance in the reverse direction until such time the spring urged member passes

over the ridge to engage the first mentioned incline surface whereby said member will actuate the sleeve relative to the shaft to separate the contact member quickly.

- 5 7. In an electric switch the combination comprising, stationary contacts; a movable contact; a slidable member carrying cam means and supporting the movable contact; an actuator slidably mounted with respect to the slidable member; 10 releasable holding means cooperating with the cam means; resilient means resisting movement of the actuator in one direction; resilient means urging the movable contact toward the stationary contacts; means for moving the actuator in one direction, said actuator when moved in said specified one direction is capable of moving a certain distance relative to the slidable member before engaging the slidable member to move same and the movable contact into engagement with the stationary contacts, said slidable member gradually compressing the second mentioned resilient means after the movable contact engages the stationary contacts to increase the contact pressure between the contacts, and said releasable holding means cooperating with the cam means 15 to hold the slidable member against retrograde movement on slight retrograde movement of the actuator so as to maintain full pressure between the contacts up to the time the actuator moves the slidable member a certain distance in the reverse direction when the holding means moves the slidable member relative to the movement of the actuator in the reverse direction to separate the movable contact from the stationary contact 20 with a snap action.
